MOLDING FOR ESCUTCHEON OR SIMILAR ARTICLE

Frank A. Holmes, La Habra, and Lawrence McCain,
Beverly Hills, Calif., assignors to Ajax Hardware
Manufacturing Corp., City of Industry, Calif., a cor-
poration of California

Filed June 18, 1968, Ser. No. 12,419

Term of patent 14 years

Int. Cl. D8—03

U.S. Cl. D8—179

FIG. 1 is a front elevational view of our design for molding for escutcheon or similar article;

FIG. 2 is a side elevational view;

FIG. 3 is an end elevational view; and

FIG. 4 is a fragmentary section as shown by the broken line 4—4 of FIG. 1.

We claim:

The ornamental design for a molding for escutcheon or similar article, as shown.
